PRESSURE RESPONSIVE DEVICE

Charles D. Branson, Knoxville, Tenn., assignor to
 Robertshaw-Fulton Controls Company, a corporation of Delaware

Application May 13, 1946, Serial No. 669,439

3 Claims. (Cl. 137—156.5)

1

This invention relates to pressure responsive devices of the type employing an expandable and collapsible chamber that includes a flexible wall that may be injured by excessive pressure.

Pressure responsive devices including an expandable and collapsible corrugated tubular wall or bellows having a movable end wall operatively connected to a means to be controlled and associated with a relatively rigid wall enclosing the corrugated wall and providing therewith an expandable and collapsible chamber are well known in the art, said chamber sometimes, as in known forms of thermostat, containing a temperature responsive medium whose pressure varies with the temperature, but more commonly such chamber is connected through an interposed conduit with a source of pressure which may be a bulb containing a temperature responsive medium in the case of a thermostatic installation or such conduit may connect with any suitable source of fluid pressure, whether liquid, vapor or gaseous, in other known forms of installation. With structures of this character it is common practice to provide means for limiting the extent of movement of the aforesaid movable end wall, as by providing cooperating stop members in association with the operative connections between said movable end wall and the means to be controlled, not only to avoid injury to said means to be controlled or the connections leading thereto in the event of excess pressure developing in said expandable and collapsible chamber, but also to avoid flexure of said corrugated wall to an extent that said wall may take a permanent set or become otherwise injured due to excessive flexure.

Expandable and collapsible corrugated tubular walls or bellows of the character referred to are commonly made of metal on the order of five or six thousandths of an inch in thickness, and metal of this thinness is easily stressed by excessive pressures, which may result in buckling or distortion of the wall, or, if the wall is not immediately deformed, the excess pressure may develop large stresses per unit area which will result in a premature failure of the flexible wall under repeated flexure during the normal and intended operation of the device.

It is an object of this invention to provide a device of the character described which automatically operates to predetermine the maximum pressure that may develop on the flexible wall and thereby avoid the undue stresses generated therein which may result in deformation or premature rupture thereof.

Another object of this invention is to provide

2

a device of the character described with means for protecting the flexible wall against excessive pressure which does not interfere with the sensitive response of such wall to varying pressures within the normal and intended range of operation of the device.

Another object of this invention is to provide a device of the character described wherein the means for protecting the flexible wall from excessive pressure is simple in construction, economical to produce and apply, and highly efficient in operation.

Other objects of this invention will appear as the description of the invention proceeds.

15 The invention is capable of receiving a variety of mechanical expressions, only one of which has been illustrated on the accompanying drawings, but it is to be expressly understood that the drawings are for purposes of illustration only, and 20 are not to be construed as a definition of the limits of the invention, reference being had to the appended claims for that purpose.

25 Referring in detail to the drawings wherein the same reference characters are employed in both figures to designate corresponding parts,

Fig. 1 is an axial section, partly broken away, and somewhat diagrammatic in character, illustrating an embodiment of the invention; and

30 Fig. 2 is a cross section taken on line 2—2 of Fig. 1 and looking in the direction of the arrows.

Referring in detail to the drawings, the embodiment shown comprises an expandable and collapsible chamber 10 formed between a generally cup-shaped rigid wall 11, of any suitable size, construction and material, and an expandable and collapsible corrugated tubular metal wall, or bellows 12, likewise of any suitable size, construction and material, said wall 12 being provided with an end wall 13, integral therewith or suitably attached thereto, to which is attached

35 in any suitable way appropriate connections to means to be controlled, here shown as in the form of a post or rod 14 attached to the end wall 13 by means of a suitable fixture 15. As is common in structures of this character the stationary end of the wall 12 is suitably secured, as by soldering or brazing, to an annular plate 16 apertured at

40 17 to permit free passage of the rod or post 14 and having its outer periphery suitably secured to the open end of the cup-shaped wall 11, as by spinning the open end of said cup-shaped wall 11 around the external periphery of the plate 16, as shown at 18, the joint between these two parts being preferably brazed or soldered to assure a hermetic joint. At a suitable point in

45 50 55

said cup-shaped wall 11 a nipple 19 or other suitable connector is hermetically sealed into the wall and any suitable conduit, whether rigid or flexible and extending to any suitable distance, may communicate with a thermostatic bulb or with any suitable source of fluid pressure which, by communication with said chamber 10, will effect the expansion and contraction of said chamber to actuate the means to be controlled.

In conformity with the present invention means are associated with said expansible and collapsible wall 12 to predetermine the extent to which said wall may be collapsed under pressure and thereafter to seal said wall from any further increase in the actuating pressure so as to preclude injury of said wall by such increase in pressure after said means to be controlled has been moved to its limit position. To this end a generally cup-shaped shield 20 is mounted on the movable end wall of the bellows 12 and secured thereto in any suitable way, as by a projecting collar 21 on the fixture 15 which may be spun into locking relationship therewith as illustrated. If said shield is to perform no guiding function for the expansive and collapsive movements of the wall 12 its peripheral wall may have any suitable clearance with the cylindrical wall of the cup 11 so as to assure that the actuating fluid may have free access to the interior of the shield 20. By preference, however, the shield aids in guiding the expansive and collapsive movements of said wall 12, and to this end an intermediate portion 22 of the peripheral wall thereof is made of ribbed, serrated or corrugated construction, as shown in Fig. 2, so as to provide channels for the free flow of fluid therewith while the tips of the ribs, serrations or corrugations have slidable contact with the inner surface of the cylindrical wall of the cup 11 so that the wall 12 is accurately guided in an axial direction as said wall expands and contracts. While reliance may be placed on the engagement of the extremity of the shield 20 with the end of the chamber 10 to effect the sealing of the pressure in the chamber 10 away from the wall 12 when the latter has moved to its extreme position, a gasket 23 of any suitable material such as will not deteriorate under the action of the fluid in the chamber 10, neoprene for example, is preferably fixedly secured in position between the periphery of the plate 16 or the end of the bellows secured thereto and a shoulder 24 on the cup 11 to provide a yielding seat for the edge 25 of the cup 20, said gasket also facilitating the making of a hermetic seal between the cup 11 and plate 16.

The peripheral wall of the shield 20 is of such length axially that when the pressure in the chamber 10 has risen to such a value as, in conformity with the intended operation of the device, to cause the expansible and collapsible wall 12 to be contracted to that position in which the means to be controlled has been operated through the post or rod 14 to its limit position, the extremity 25 of said shield 20 will make a fluid tight engagement with the gasket 23 and thereby seal or isolate the space 26 within the shield 20 from any further increase of pressure in the chamber 10. Thus, as sometimes occurs in practice, the pressure in the chamber 10 may continue to rise because of a lag in the response to the repositioning of the controlling means, but with the present invention there is no increase of the pressure acting on the wall 12 after the latter has moved to a predetermined position

corresponding to the limit position of the means to be controlled whereby said wall 12 is shielded from the excess stresses or deformation that would otherwise result from such increase in pressure. On the other hand, the pressure required to flex the wall 12 to its extreme position is trapped within the shield 20, so that as soon as the pressure in the chamber 10 decreases to a value below that required to flex the wall 12 to its extreme position the pressure internally of the shield will effect an expansion of the wall 12 so that the latter will move the means to be controlled in the opposite direction at the required decrease in pressure as if no shield were present, thereby opening the chamber 26 inside of the shield 20 to the pressure in the chamber 10.

It will therefore be perceived that by the present invention a pressure responsive device employing a highly sensitive flexible wall is not only provided with means for predetermining the extent to which said wall may be collapsed by the actuating pressure, taking the place of the stop devices heretofore employed for preventing an excessive collapse of said wall, but as soon as said wall has been flexed to its limit position it is immediately and automatically shielded upon any further increase in the actuating pressure so that overstressing of said flexible wall or deformation thereof arising from further increase of pressure in the chamber 10 has been entirely avoided. Also the construction is such that immediately the pressure drops below that value at which the wall 12 is moved to its limit position the pressure of the trapped fluid inside of the shield acting on the larger effective area of the end wall of the shield will cause a prompt expansion of the bellows 12. The shield is of a simple construction that can be readily formed by stamping from sheet metal, and it may be readily secured in position by spinning as heretofore pointed out, so that the shielding provision is inexpensive and economical to fabricate and assemble.

While the embodiment of the invention illustrated on the drawing has been described with considerable particularity, it is to be expressly understood that this embodiment has been selected merely for the purpose of exemplifying the invention, and that as will now be apparent to those skilled in the art the invention may be embodied in a variety of constructions and changes may be made in the details of construction, form, size, proportion, arrangement, etc., without departing from the spirit of this invention. Reference is therefore to be had to the appended claims for a definition of the invention.

What is claimed is:

1. In a pressure responsive device of the type including a rigid enclosure and a flexible expansible and collapsible corrugated wall disposed interiorly of said enclosure and forming therebetween an expansible and collapsible chamber to be subjected to fluid under pressure, said flexible wall having a movable end wall operatively connected to a means to be controlled, a cup-shaped imperforate shield mounted on said movable end wall and disposed in said expansible and collapsible chamber in surrounding relationship to said flexible wall, said cup-shaped shield being movable with said end wall under increase of pressure in said chamber to engage its free end in fluid sealing relation with said enclosure after a predetermined increase of pressure in said chamber to enclose and shield said flexible wall against further increase of pressure in said chamber,

said cup-shaped shield being provided on its peripheral wall with spaced axially extending outward projections cooperating with said enclosure to guide the movement of said shield and being constructed and arranged to preclude passage of fluid into the interior thereof when said free end thereof is in engagement with said enclosure.

2. In a pressure responsive device of the type including a rigid enclosing wall, an apertured plate coacting with the enclosing wall to form a rigid enclosure, sealing means between the enclosing wall and the apertured plate, and a flexible expandable and collapsible corrugated wall disposed interiorly of said enclosure and forming therebetween an expandable and collapsible chamber to be subjected to fluid under pressure, said flexible wall being secured at one end to said apertured plate and having a movable end wall adapted to be operatively connected to a means to be controlled, a member mounted on said movable end wall and disposed in said expandable and collapsible chamber, said member being movable with said movable end wall under increase of pressure in said chamber to engage said sealing means at a predetermined increase of pressure in said chamber to form a shielding enclosure for said flexible wall and being constructed and arranged to preclude passage of fluid into said enclosure when in engagement with said sealing means.

3. In a pressure responsive device of the type including a rigid enclosing wall, an apertured plate coacting with the enclosing wall to form a

rigid enclosure, sealing means between the enclosing wall and the apertured plate, and a flexible expandable and collapsible corrugated wall disposed interiorly of said enclosure and forming therebetween an expandable and collapsible chamber to be subjected to fluid under pressure, said flexible wall being secured at one end to said apertured plate and having a movable end wall adapted to be operatively connected to a means to be controlled, a cup-shaped imperforate shield mounted on said movable end wall and disposed in said expandable and collapsible chamber in surrounding relationship to said flexible wall, said cup-shaped shield being movable with said end wall on increase of pressure in said chamber to engage said sealing means to effect a seal therewith and provide a fluid-tight enclosure for said flexible wall shielding said flexible wall against further increase or pressure in said chamber.
